NOZZLE

Ferdinand G. Schloz, Philadelphia, Pa.

Application April 25, 1939, Serial No. 269,849

2 Claims. (Cl. 299—120)

My invention relates to a sprayer or spray nozzle which is adapted for various uses but is primarily designed as a fluid fuel atomizer.

My improvements are primarily designed to provide a sprayer in which danger of clogging the passages by dirt or congealed liquid is reduced to a minimum; in which a curvilinear or helical motion is imparted to the liquid prior to its admission to a swirling chamber adjacent the exit orifice; and from which the atomized liquid is discharged as a conoidal cloud of substantially uniform density.

My improvements are preferably embodied in a sprayer having its swirling chamber fed through ducts from which liquid is discharged both tangentially to the annular wall of the swirling chamber, to form the peripheral portion of the vaporous jet, and at or toward the center of the swirling chamber, to form the center of the vaporous jet. Some or all of the ducts through which the liquid is fed are so curved or inclined as to impart a circular or helical movement and apply centrifugal force to the flowing liquid. Where very small quantities of liquid are being fed, the direction of movement and the force imparted thereto by such curved ducts before entering the swirling chamber may so unify the density of the vaporous jet produced therefrom as to render unnecessary the feeding of auxiliary liquid to or toward the center of the swirling chamber.

The sprayer preferably comprises a hollow shell, containing a spray orifice, and a body housed therein and having grooved surfaces complementary to surfaces of the shell to provide liquid supply ducts. The telescoped body also has surfaces spaced from complementary surfaces of the shell to form a series of chambers connected by the ducts and terminating in a swirling chamber discharging to the spray orifice.

The forepart of the body may be recessed axially so as to provide an extension or enlargement of the swirling chamber and permit the axial introduction of liquid into the swirling chamber through such extension without intersecting or disrupting the wall of liquid formed in the swirling chamber by liquid delivered thereto through curved ducts in the face of the body. Such face of the body and a complementary surface of the shell are preferably conoidal and abutted closely against one another in concentric relation, preferably by screwing a threaded shoulder of the body into the threaded inner wall of the shell. The concentricity of the threading, facing and grooving of the body is insured by providing the body with a tapered chucking

shank for mounting it during the threading, facing and grooving operations.

The threaded shoulder of the body may be grooved diagonally to the threads and to the axis of the body to provide ducts connecting the inlet chamber with a second chamber of the sprayer and impart an initial rotary movement and centrifugal and atomizing force to the liquid so that thereby, and by the curvature of ducts leading to the swirling chamber, the velocity of the liquid is increased, abrupt changes in the direction thereof in its flow to the swirling chamber are minimized, the ducts and chambers are scoured to prevent any clogging thereof by dirt or congealed oil, and the peripheral wall of liquid is caused to so hug the wall of the swirling chamber so as to permit the use of a larger orifice for the same capacity output.

The advantages of my improvements are most pronounced when all the features thereof are embodied in a single structure, but certain of the advantages of my improvements may be obtained even though one or more of the preferred features are omitted or modified.

25 The characteristic features and advantages of my improvements will further appear from the following description and the accompanying drawing in illustration of various embodiments of my invention.

30 In the drawing,

Fig. 1 is a longitudinal sectional view of a sprayer embodying my invention;

Fig. 2 is a top plan view of the body of the sprayer shown in Fig. 1;

35 Fig. 3 is a longitudinal sectional view of a sprayer having a body differing in details from the body of Figs. 1 and 2;

Fig. 4 is a top plan view of the body shown in Fig. 3; and

40 Fig. 5 is a part sectional elevation of a sprayer having a shell similar to those shown in Figs. 1 and 3 but a further modified body.

In the embodiments of my invention illustrated in the drawing, a hollow shell or tip has a tapering nose 1, containing an orifice 2 at its apex, a polygonal shoulder 3, and an exteriorly threaded shank 4 adapted to be screwed into a supply pipe fitting so that the radial face of the shoulder is moved into abutting, sealing relation to the end wall of the fitting. The inner surface of the shell has a conoidal section 5 at the forepart thereof, a smooth cylindrical intermediate section 6, and a threaded cylindrical section 7 at the base thereof.

45 The shell contains a complementary body or

plug forming therewith a swirling chamber 8 discharging through the orifice 2, an intermediate chamber 9 and an inlet chamber 10 into which liquid under pressure is delivered from the supply pipe.

The body or plug has a conoidal face 11 abutting the surface 5, a cylindrical surface 12 spaced from the surface 6, an enlarged threaded shoulder 13 screwed into the threaded section 7 and a conoidal shank 14. The shank 14 may terminate in a cylindrical butt 15 containing a diametral slot 16 as shown in Figs. 1, 5, or the butt may be eliminated and a diametral slot 16' cut in the bottom of the shank as illustrated in Fig. 3. The taper of the shank 14 not only gradually decreases the cross section of the chamber 10 but also provides a hold by which the body may be chucked to turn the face 11 and threaded shoulder 13 in true concentricity with each other and with the surface 5 so as to insure flush contact between the surface 5 and face 11 when the body is screwed up tight in the shell.

The shoulder 13 is intersected by slots 17 extending diagonally of the body axis so that streams of liquid flowing from the inlet chamber 10 to the intermediate chamber 9 strike the curved wall thereof at angles which impart helical or curvilinear motion to the streams.

In the embodiment illustrated in Figs. 1 and 2, the head of the body is recessed to provide a chamber 18 having an upper edge coterminous with the lower edge of the chamber 8. The bottom of the chamber 18 is constricted to form an axial passage 19 into which liquid is tangentially discharged through the transverse passages 20 communicating with the chamber 9.

The conoidal face 11 contains curved grooves or ducts 21 leading from the chamber 9 to the chambers 8 and 18 adjacent to the juncture between their coterminous edges. Preferably the curvature of the outer wall of each groove 21 has a radius approximately equal to one half the length of a straight line drawn from a point in the inner or top edge of the face 11 through the body axis to a diametral point in the outer or bottom edge of the face 11 plus one half the width of the groove. The center of the curve is at a point substantially midway the length of such straight line. When the outer curve of the groove is so shaped it coincides at its inner end with the wall of the swirling chamber and the emitted jet is so directed as to leave no open space between the jet and the wall of the swirling chamber. The inner wall of each groove is concentric with the outer wall thereof and coincides at its outer end with the cylindrical face of the body.

The curvature of the grooves may, however, be varied within the scope of my invention so long as adequate curvilinear motion and centrifugal force is imparted to the liquid without unduly retarding the flow. Generally this will be accomplished if the curvature of each groove 21 is such that the angle between lines drawn from the longitudinal axis of the sprayer to the intersections of the center line of the groove with the edges of the face 11 is not less than 90° nor more than 180°.

The jets emitted from the curved ducts 21 contact the annular walls of the chambers 8 and 18 without appreciable impact and are given a swirling motion forming an annular wall around the swirling jet emitted from the passage 19. The swirling streams of liquid are emitted from the orifice 2 as atomized particles forming a conoidal cloud of substantially uniform density. The

curvilinear motion and centrifugal force imparted to the liquid in passing from the chamber 10 to the swirling chambers 8 and 18, and the elimination of abrupt changes in the direction of flow, 5 scour the passages and augment the rate of flow and the nebulizing of the liquid.

In the embodiment illustrated in Figs. 3 and 4, the head and stock of the body are made in two pieces instead of being made integrally as in Figs. 10 1 and 2. The stock has its upper end cylindrically recessed to receive the base of the head which has its lower edge undercut so as to form 15 with the body an annular channel 20' communicating with the chamber 9 through the ports 20''. The bottom of the head has a face having its 20 inner circular edge coincident with the bottom of the passage 19 and its outer circular edge coincident with the bottom inner edge of the channel 20'. The bottom face of the head contains 25 grooves 20a connecting the channel 20' with the passage 19 and each curved on a radius equal to one-half the length of a line drawn from a point in the inner edge of the face, through the axis of the body to a diametral point in the outer edge of the face plus one-half the width of the groove. The center of each groove lies midway the ends of such a line and the grooves are equidistantly spaced. The curvature of the ducts 20a has an 30 effect upon liquid flowing therethrough similar to the effect imparted by the curved ducts 21 to liquid flowing therethrough.

Where the volume of liquid to be sprayed is small, the body chamber 18, passage 19, and ducts leading therethrough may be eliminated, as 35 shown in Fig. 5. In such case the curved ducts 21 discharge directly into the swirling chamber 8 whose bottom is formed by the flattened front end of the body, and the force and direction imparted to the liquid prior to its introduction into 40 the swirling chamber 11 serve to insure the atomization thereof in a conoidal cloud having a desired uniformity of density.

By my improvements sudden changes of direction of flow of the liquid are minimized with 45 consequent reduction in friction and in the formation of eddies and liquid is supplied to the center of a jet with minimum interference with the supply of liquid to the periphery of the jet. My improvements further permit the orifice to 50 be made of larger area for the same rated capacity, while still giving an increased velocity and decreased danger of clogging.

Having described my invention I claim:

1. A sprayer comprising a hollow shell containing a spray orifice, and a body housed in said shell and having a forepart forming a conoidal face with its upper edge spaced from the longitudinal axis of the sprayer and its lower edge concentric with such axis, said body having surfaces complementary to and spaced from surfaces of said shell to form chambers including a swirling chamber discharging through said spray orifice, said face containing grooves and being positioned adjacent to a complementary surface of said shell to provide liquid supply ducts to said swirling chamber from another chamber aforesaid, the grooves in said face comprising a plurality of symmetrically disposed curved grooves and the curvature of the outer wall of each groove having a radius approximately equal to one-half the length of a straight line drawn from a point in the upper edge of said face, through said axis to a diametral point in the bottom edge of said face plus one-half the width of the groove; the 70 center of curvature of such outer wall being at 75

a point substantially midway the length of such straight line, and the outer curve of each groove substantially coinciding at its inner end with the wall of the swirling chamber so as to leave no open space between a jet emitted from such groove and the wall of the swirling chamber; and the inner wall of each groove having a curvature concentric with the curvature of the outer wall thereof.

2. A sprayer comprising a hollow shell containing a spray orifice and a two-piece body housed in said shell and forming therewith a plurality of

chambers including a swirling chamber adjacent to said spray orifice, one of said body pieces being threaded into said shell and containing ducts extending transversely to the axis of said sprayer, and the other of said body pieces containing an axial passage and curved ducts communicating with said axial passage and with said ducts first named, and said second body piece also containing curved ducts in the surface of the forepart thereof and communicating with said swirling chamber independently of said axial passage.

FERDINAND G. SCHLOZ.
